(57) **CLAIM**

The ornamental design for an adhesive tape with protective case, as shown and described.

DESCRIPTION

FIG. 1 is a first perspective view of an adhesive tape with protective case showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the adhesive tape with protective case thereof;

FIG. 10 is a perspective view of another state of the adhesive tape with protective case thereof; and,

FIG. 11 is an exploded view of the adhesive tape with protective case thereof.

The broken lines shown in the drawings depict portions of the adhesive tape with protective case that form no part of the claimed design.

1 Claim, 11 Drawing Sheets
